(57) **CLAIM**

The ornamental design for a hand paint mixer, as shown and described.

DESCRIPTION

FIG. 1 is a perspective view of a hand paint mixer showing my new design in the environment of a paint can.

FIG. 2 is a front elevation view of the hand paint mixer of FIG. 1.

FIG. 3 is a rear elevation view thereof.

FIG. 4 is top plan view thereof.

FIG. 5 is a bottom plan view thereof.

FIG. 6 is a right side elevation view thereof; and,

FIG. 7 is a left side elevation view thereof.

The broken lines in FIG. 1 illustrate environmental structure and form no part of the claimed design.
